UNITED STATES PATENT OFFICE.

ANTHONY TORTORICH AND EDWARD FONTAINE WILKINSON, SR., OF LUTCHER,
LOUISIANA.

BOILER.

Application filed September 3, 1924. Serial No. 735,668.

To all whom it may concern:

Be it known that we, ANTHONY TORTORICH and EDWARD F. WILKINSON, Sr., citizens of the United States, residing at Lutcher, in 5 the parish of Saint James and State of Louisiana, have invented new and useful Improvements in Boilers, of which the following is a specification.

This invention relates to heating devices, 10 particularly to boilers, and has for its object the provision of a novel boiler designed for domestic use for heating water for bathing or other purposes, or for boiling clothes.

An important object is the provision of a 15 boiler which is so constructed and arranged as to utilize practically any kind of fuel either solid, liquid or gaseous, the device being however provided with a grate whereby charcoal may be burned with ease.

20 Another object is the provision of a device of this character in which the water receptacle is removable and consequently capable of being transported to wherever its use is desired without it being necessary to 25 move the entire device.

The invention further contemplates the 30 improvement of devices of this general class not only in the details of construction and arrangement but also in the combination of parts whereby maximum efficiency will be attained.

An additional object is the provision of 35 a device of this character which will be simple and inexpensive in manufacture, easy to use and operate, positive in action, efficient and durable in service, and a general improvement in the art.

With the above and other objects and advantages in view, the invention consists in 40 the details of construction to be hereinafter more fully described and claimed, and illustrated in the accompanying drawings, in which:

Figure 1 is a front elevation of the complete device.

Figure 2 is a longitudinal vertical section therethrough.

Figure 3 is a cross section on the line 3—3 of Figure 2.

50 Figure 4 is a cross section on the line 4—4 of Figure 2.

Figure 5 is a top plan view of the flue cover.

Referring more particularly to the drawings, we have shown our device as comprising

ing a base member designated broadly by the numeral 10, which base member is preferably formed as a cylindrical shell 11 having supporting legs or feet 12 and provided at its top with an inwardly extending flange 13 crimped or otherwise formed at its juncture with the wall of the cylindrical shell to define what may be termed the bead 14.

The numeral 15 designates the boiler which is likewise cylindrical in shape and 65 preferably of the same diameter as the base. This boiler includes a side wall or shell 16 and a bottom member 17 which rests upon the flange 13. At the juncture of the bottom and the shell is a bead 18 which fits within 70 the bead 14 above described, the latter constituting a seat for holding the boiler in proper position upon the base. Near its upper portion this boiler is provided with any desired number of suitable handles 19 where- 75 by it may be lifted about from place to place as needed.

Extending axially of the boiler is an elongated upstanding cylindrical flue 20 which is suitably secured to the bottom 17 of the 80 boiler as shown and which has its lower end extending downwardly below this bottom member 17 but terminating above the lower portion of the base. Surrounding the flue is a shell member 21 which is likewise secured 85 to the bottom 17 and which is formed throughout its area with a plurality of perforations 22 permitting the passage of hot water therethrough.

The shell member 21 terminates slightly 90 below the upper edge of the boiler shell 16 while the flue member 20 extends considerably above such edge as clearly indicated in Figure 2. In order that the top of the flue might be closed, we make use of a cylindrical cover member 23 which is formed with a circular series of holes 24. Pivoted or rotatably mounted by a pivot pin 25 on the top of the cover 23 is a disk 26 equipped with a control handle 27 and formed with a 100 circular series of holes 28 adapted to be brought more or less into registration with the holes 24 for controlling the draught through the flue. The top of the boiler 15 itself is adapted to be closed by means of an annular 105 frusto-conical cover 29 having a depending flange 30 telescoping within the boiler shell and having an outstanding bead 31 feeding upon the upper edge of the boiler shell for preventing the cover from slipping too far 110

inwardly. This cover member 29 is obviously so constructed that it will have a central hole of sufficient size to engage upon the outside of the flue member and make a comparatively tight joint.

6 While it is quite true that any desired heating means might be provided within the flue, we have shown a grate formed as disk 32 having a series of holes 33 therethrough 10 permitting the passage of air. This grate is pivotally mounted within the flue by means of trunnions or pins 34 and is adapted to serve as a support for charcoal, coke or other solid fuel. Logically, it is necessary that 15 this grate be capable of shaking or dumping from the outside of the device and for this reason we provide an elongated rod 35 which is equipped at the front end of the machine with a handle 36 and which is connected at 20 37 with an arm 38 depending from the center of the disk 32. By properly manipulating the handle 36 it is evident that the grate disk may either be shaken or dumped entirely so as to discharge any ashes accumulated 25 thereon. Located in the lower portion of the base member 10 are spaced parallel guides 39 which support an ash can 40 which is capable of being slid out through an opening 41 in the front of the base, which 30 opening is normally closed by a plate 42 equipped with a handle 43 and formed with spaced elongated slots 44 normally engaging over headed studs or the like 45. After this plate is removed it is evident that the operator may reach in and grasp the handle 46 of the ash pan and draw it out so that any accumulation of ashes therein may be dumped in a very easy manner.

40 To effect filling of the boiler with water, it is necessary to remove the cover 29 but in order that the water may be easily withdrawn for use after it is heated, we make use of a drain cock 47 mounted on the boiler at the lower portion thereof.

45 In the operation, heat is applied within the flue 20 and in actual practice, as mentioned above, charcoal, coke or the like may be utilized as a fuel. This fuel is placed upon the disk-like grate and is ignited by 50 any suitable means and it is evident that the heat generated will efficiently operate to heat the water within the boiler. Hot water may be withdrawn from the faucet or cock 47 at any time. In case the device is used in the 55 laundry for boiling clothes, it is evident that the perforated shell member 21 will prevent the clothes from coming in contact with the wall of the flue and becoming scorched thereby.

60 From the foregoing description and a study of the drawings it will be apparent that we have thus provided a simply constructed, inexpensive and very efficient de-

vice for the purpose specified which will be 65 a great time and labor saver, especially in communities where gas and electricity are not available.

While we have shown and described the preferred embodiment of the invention, it 70 should be understood that we reserve the right to make such changes in the form, construction and arrangement of parts as will not depart from the spirit of the invention or the scope of the subjoined claims. 75

Having thus described the invention, we claim:

1. A device of the character described comprising a cylindrical base member open at its bottom and provided at its top with an 80 inwardly extending supporting ring portion, the base member being provided with legs the spaces between which constitute draft openings, an ash pan removably mounted within said base member, a cylindrical boiler registering with and mounted upon the base member, the boiler having a bottom member and a removable cover, said bottom of the boiler resting upon the inwardly directed ring portion at the upper 85 edge of the base member, a cylindrical flue extending axially through the boiler and having its lower end secured to and projecting beyond the bottom thereof and terminating at a point above said ash pan, an annular perforated wall member surrounding 90 said flue in spaced relation thereto, a grate located within the lower portion of the flue, and a removable cover for the flue provided with draft regulating means. 95

2. In combination, a cylindrical base member provided at its lower edge with supporting legs, the spaces between the legs constituting draft openings, an ash pan removably mounted within said base, a boiler removably mounted upon the base and likewise of cylindrical formation and registering with the base, said boiler having its top open and having its bottom closed by a wall member, a cylindrical flue located axially of the boiler and having its upper end projecting beyond the top thereof, the said flue being secured to the boiler bottom and projecting therebeyond, a cover of ring-like formation 110 closing the upper end of the boiler and arranged in surrounding relation to the upper end of the flue, a cover for the flue independent of said first named cover and provided with draft control means, and a movably mounted grate located within the flue and adapted to support fuel during the process 115 of combustion. 120

In testimony whereof we affix our signatures.

ANTHONY TORTORICH.
EDWARD FONTAINE WILKINSON, Sr.
